(57) **CLAIM**

The ornamental design for a “portable liquid warmer,” as shown and described.

DESCRIPTION

FIG. 1 is a top perspective view of a “portable liquid warmer” showing my new design;

FIG. 2 is a right side view thereof;

FIG. 3 is a left side view thereof;

FIG. 4 is a bottom perspective view thereof;

FIG. 5 is a top plan view thereof; and,

FIG. 6 is a bottom plan view thereof.

The broken line showing of structure is included for the purpose of illustrating portions of the “article” and forms no part of the claimed design.
